United States Patent

Des. 240,764
Patented July 27, 1976

240,764

ELECTRIC GUITAR OR SIMILAR ARTICLE

Stanley E. Rendell, Kalamazoo, Mich., assignor to
Norlin Music, Inc., Lincolnwood, Ill.

Filed Sept. 23, 1974, Ser. No. 508,076

Term of patent 14 years

Int. Cl. D17—03

U.S. Cl. D56—1 A

FIG. 1 is a front elevational view of an electric guitar or similar article showing my new design;

FIG. 2 is a left side elevational view;

FIG. 3 is a right side elevational view;

FIG. 4 is a rear elevational view;

FIG. 5 is a top plan view; and

FIG. 6 is a bottom plan view.

I claim:

The ornamental design for an electric guitar or similar article, substantially as shown and described.
